UNITED STATES PATENT OFFICE.

ERNEST DIGBY HOPCROFT, OF BRIDGEPORT, CONNECTICUT, ASSIGNOR TO THE HOPCROFT GAS PRODUCER CO., OF BRIDGEPORT, CONNECTICUT.

GAS-PRODUCER.

No. 872,625.

Specification of Letters Patent.

Patented Dec. 3, 1907.

Application filed October 9, 1906. Serial No. 338,133.

To all whom it may concern:

Be it known that I, ERNEST DIGBY HOPCROFT, a subject of the King of the United Kingdom of Great Britain and Ireland, residing at Bridgeport, in the county of Fairfield and State of Connecticut, have invented certain new and useful Improvements in Gas-
Producers, of which the following is a specification, reference being had therein to the accompanying drawings.

My invention relates to gas producers and more particularly to a class thereof especially designed and adapted to produce gas from coal for industrial or power purposes.

15 The main object of the invention is to provide a gas producer wherein gas will be generated from a partially incandescent body of coal by drawing therethrough an admixture of vapor and the products of combustion of 20 the gas generated and subsequently ignited, and wherein the quantity of gas produced will be automatically regulated to that amount being consumed and drawn from the apparatus at any given time.

25 A further object is to provide such an apparatus with means whereby the exhaust from the engine or other means consuming the gas generated, will be discharged into the retort through a channel in communication 30 with a source of vapor supply, and the velocity of the flow of said exhaust will so regulate and control the volume of such vapor entering said channel as to preserve the proper proportion of said vapor and said 35 products of combustion irrespective of the variance in the quantity of gas being produced.

A still further object is to provide a producer which by reason of the introduction of 40 heated vapors and the products of combustion, will be capable of producing power gas in such quantities and of such quality as to result in an economical maintenance and operation of the producer.

45 A still further object is to provide a producer, the construction and arrangement of which will be such as to be reasonably safeguarded against fire risks and other risks incidental to the maintenance of an isolated 50 gas producer plant.

A still further object is to provide a producer wherein liquid from which the vapors are generated may be furnished from time to time with chemicals in a solution in a manner to impart to the vapors those chemical

properties which will tend to increase the quantity and improve the quality of the gases released from the incandescent coal. And a still further object is to provide a producer of this character which will be simple 60 in design and in its mode of operation and automatic in all respects except the removal of the coal supply and the cleansing of the washers, scrubbers and driers.

The invention consists in the novel features of construction hereinafter set forth and described and more particularly pointed out in the claims hereto appended.

Referring to the drawings: Figure 1 is a vertical section of the retort of a producer 70 and of one of the auxiliary tanks, embodying my invention; Fig. 2 is a side elevation thereof on a smaller scale, and Fig. 3 is a plan view of the device as shown in Fig. 2.

Like letters refer to like parts throughout 75 the several views.

In the embodiment of my invention shown in the drawings, I have shown at *a* a retort having a hopper *b* for a reserve coal supply at the top thereof. This hopper has a cover *b'* for the top thereof and an inverted bowl shaped gate *c* closing the bottom thereof and opening into the retort *a*. A weighted lever *c'* is pivoted to or adjacent to the hopper *b* and is connected to the gate *c* by a link *c'*, a 80 construction and arrangement which permits the contents of the hopper to be dumped into and distributed in, the retort while the hopper is closed, thus avoiding the escape of 85 noxious gases when the retort is being recharged. A fire grate *d* is arranged adjacent to the bottom of said retort.

Within the upper part of the retort *a* is a water-tight tank *e* which is so positioned as to be subjected to the heat generated within 95 the retort, thus vaporizing the water contained therein. A small air pipe, as *g*, communicates with this so that the vapor may, if desired be mixed with air in said tank. In practice, however, I find that enough air enters through the cracks about the covers of the various openings in the retort *a*, and that I seldom have to rely upon the pipe. Adjacent to the said vapor tank is a smaller tank *e'* adapted to contain chemicals in solution 100 which are discharged into the tank *e* as required, the water for said tank passing through said chemical tank and being automatically fed thereto by the actuation of a float valve *e''*. 110

The retort *a* is surrounded by an outer metallic casing *a'* between which and the outer wall of the retort is a space for air, which prevents the excessive heating of the outer casing. The retort *a* as is customary with producers of this character, is lined with fire clay. The lower part of the space between the walls of the retort is in communication with the interior of the retort below the 10 grate *d* through a plurality of small passages as *a'*, through which the mixture of vapor from the tank *e* and hydrogen gases and other products of combustion from the source of consumption of the gases generated pass to the base of the coal pile within the retort, from the said space.

The casing *a'* and retort *a* are provided with openings, not shown, for raking the coal in starting and removing the ash; and a 20 pipe *f* having any desired form of protected discharge nozzle *f'* within said retort and above the grate *d* is in communication with a blower *f'* preferably hand operated, whereby the atmospheric air may be forced 25 through the coal pile in starting.

Within the tank *e* is a perforated drum *g*. This drum is in communication with the lower space about said retort through a pipe *g'*, the outlet of which is controlled by an 30 ordinary damper plate *g*² having a stem *g*³ projecting through the casing *a'*.

Communicating with the space below the damper *g*² is a blower casing *h* within which is mounted a wheel *h'* having a plurality of 35 vanes *h*², each presenting rearwardly a dished surface. Actuated from the shaft of said wheel is an ordinary centrifugal governor *i* so connected to the damper stem *g*³ by the lever system *i'* as to open said damper 40 proportionately to the increased speed of rotation of the wheel *h'*.

The casing *h* is in communication with the exhaust of an internal combustion engine not shown through a pipe *h*³ thus causing the 45 engine exhaust to pass through the casing *h* actuating the wheel *h'* therein through the vanes *h*², and the damper *g*², to the space about the lower part of the retort adjacent to the discharge end of the pipe *g'* where it 50 mixes with the vapor discharged from said pipe and becomes diffused about the said retort.

Adjacent to the retort *a* are three auxiliary tanks *j*, *k* and *l* each of which is filled 55 with suitable porous, and absorbent substances to properly condense, wash, scrub and dry the gases passed therethrough. These tanks are vertically disposed and are connected in series by means of a box *m* 60 with one chamber of which the tanks *j* and *k* communicate, and a pipe *n* between the upper part of the tanks *k* and *l*. The tank *l* discharges into a second chamber in the box *m*.

65 The tank *j* is in connection with the upper

part of the retort *a* through a pipe *o* and the second chamber in the box *m* is in communication with an internal combustion engine through a pipe *o'* thus providing a continuous circulation channel from the engine cylinder through the exhaust thereof, the pipe *h*³, the casing *h*, the chamber about the lower part of the retort *a*, the retort itself, the several tanks *j*, *k*, *l* and the pipe *o'* to the inlet port of the engine. 75

The tank *j* has a water distributer *j'* at the top thereof and an outlet pipe *j*² passing from the bottom thereof and discharging into a tank *p* having an outlet above the discharge end of said pipe *j*², thus forming a 80 water seal preventing the escape of the gases through said pipe.

The bottom of the tank *j* is dished as shown to prevent the water passing to the box *m*, the openings in said bottom for the gas, 85 being above the bottom of said dished portion.

Each of the tanks *j*, *k* and *l* is provided with a plurality of grates 1-2 dividing it into three communicating compartments each of 90 which has a hand hole as 3 closed by a face plate indicated at 4 whereby the filling therein may be removed and replaced.

The two upper compartments of the tank *j* are filled with coke or some other similar 95 porous substance and the lowermost compartment with a granulated non-porous substance, as cork, through all of which water percolates serving to condense and wash and scrub the gas passing therethrough. The 100 compartments of the tank *k* are filled with an absorbent substance loosely packed therein, thus serving to dry scrub and dry the gas. The compartments of the tank *l* are filled with a dry and highly absorbent substance 105 capable of acting as a final filter and dry scrubber and drier for the gases.

The operation of the herein described producer is substantially as follows: In starting, a fire is built upon the grate *d* and coal introduced to the retort in such quantities as may be required to secure an incandescent body of coal sufficient to maintain a slow combustion within the retort. Thereafter the retort is closed and the fire permitted to 115 smolder until the water in the tank *e* is partly vaporized. Atmospheric air is then forced through this body of coal by means of the hand blower *f'*, pipe *f* and the discharge nozzle *f'* thereof, to release the carbonic acid 120 gases in the coal and mix with them the constituent gases of the air to produce a combustible mixture for the initial charge for the engine or other source of power utilizing this gas. These producers have their highest 125 efficiency in connection with internal combustion engines and the continuous operation of the producer will be described in connection therewith. The producer, however, may be used in various connections with 130

economy, and it is not my intention to in any way limit the uses of the invention to such engines. A quantity of free gas having been thus liberated within the retort *a*, the 5 engine is started and the suction of the piston draws this gas or a portion thereof through the pipe *o* and the tanks *j k* and *l* and pipe *o'*. In the first of these tanks, *j*, it is thoroughly washed, condensed and 10 scrubbed. In the tank *k* to which the gas passes through the box *m*, it is dry scrubbed and dried to a great extent, and in the tank *l* it receives a further dry scrubbing and drying and a final filtration preparatory to passing 15 to the engine. The water constantly percolating through the filler of the tank *j* not only serves to wash the gas, but to carry away through the pipe *j'* and tank *p* some of the tar and other by-products deposited on 20 the said filler. The exhaust of the engine is forced through the pipe *h* to the casing *h* where it rotates the wheel *h'* through the vanes *h* thereon, passing from said casing to the space about the retort. The speed of 25 rotation of the wheel is governed by the velocity of the exhaust, and as the centrifugal governor is actuated thereby, the damper plate *g* is opened to an extent to allow vapors formed in the tank *e* to pass from the 30 pipe *g'* and mix with the incoming products of combustion. This mixture becomes diffused about the lower part of the retort and with each successive cycle of the engine, is drawn through the openings *a* and the entire 35 body of incandescent coal, serving to disrupt the carbon elements and form a mixture of the carbonic acid gases, carbon monoxid, hydrogen and nitrogen, which produces a highly combustible mixture and one 40 having such power as to insure high efficiency, and economy. The water in the tank *e* is replenished from the chemical tank *e'* from time to time, such chemicals being employed as will give to said water and the 45 steam generated therefrom, those properties best calculated to give the best results in operating the apparatus.

It will be observed that the greater the power developed by the engine, the larger 50 will be the quantity of gas withdrawn from the producer, and the greater the volume of the exhaust gases discharged through the casing *h*, the velocity of the flow also being increased. As the governor is actuated 55 through the velocity of the flow of the exhaust gases, with the increase of said velocity and consequent increase of the volume of such gases passed through the casing *h*, the damper *g* will be opened so as to insure 60 the feeding of a proportionately increased volume of steam through the pipe *g'* to secure a uniform mixture of the gases passed through the openings *a* to the retort.

The passage of an increased volume of this 65 mixture through the pile of coal will raise the

temperature within the retort *a* thus increasing the volume of steam generated. Hence the capacity of the producer is automatically increased or diminished throughout to adjust the quantity of gas generated 70 to that demanded, and the quality of the mixture, and of the gases produced will remain substantially the same.

When it is required to renew the supply of coal, or recharge the retort, the cover *b'* is 75 opened and the hopper *b* filled with coal, the said cover then being replaced and secured in place. The handle *c'* is then raised dropping the gate *c* from the mouth of the hopper and permitting the coal to enter the retort. It 80 will be observed that the gate *c* will normally seal the hopper mouth thus preventing the escape of the gases when the lid *b'* is raised.

It is not my intention to limit the invention to the precise details of construction 85 heretofore described, it being apparent that such details may be varied without departing from the spirit and scope of the invention.

Having described the invention, what I 90 claim as new and desire to have protected by Letters Patent is:—

1. In a gas producer, the combination of a retort, means in communication therewith whereby gas generated therein is washed, 95 scrubbed and dried, a distributing chamber in communication with the lower part of said retort, a vapor tank, means whereby said tank is placed in communication with said chamber, means whereby gases are introduced to said chamber in volume proportionate to the quantity of gas drawn from said retort including a blower casing, a wheel mounted therein having vanes whereby said gases will rotate said wheel, a governor actuated by said wheel, a damper plate or valve, and connections between said governor and said plate or valve whereby the volume of steam admitted to said chamber is automatically controlled to preserve the proportions of said vapor and said gases in the 100 mixture in said chamber.

2. In a gas producer, the combination of a retort, means in communication therewith whereby gas generated therein is washed, 115 scrubbed and dried, a distributing chamber in communication with the lower part of said retort, a vapor tank, a tank adapted to contain chemicals in communication with said vapor tank, means whereby said tank is 120 placed in communication with said chamber, means whereby gases are introduced to said chamber in volume proportionate to the quantity of gas drawn from said retort including a blower casing, a wheel mounted 125 therein having vanes whereby said gases will rotate said wheel, a centrifugal governor actuated by said wheel, a damper plate or valve, and connections between said governor and said plate or valve whereby the vol- 130

ume of steam admitted to said chamber is automatically controlled to preserve the proportions of said vapor and said gases in the mixture in said chamber.

5. 3. In a gas producer, the combination of a retort, means in communication therewith whereby gas generated therein is washed, scrubbed and dried, a distributing chamber in communication with the lower part of said retort, a vapor tank, means whereby gases are introduced to said chamber in volume proportionate to the quantity of gas drawn from said retort including a perforated drum, a pipe leading therefrom and opening into said chamber, a damper plate or valve in said pipe, a blower casing communicating with said chamber, a wheel therein having vanes whereby said gases will rotate said wheel, a centrifugal governor actuated by said wheel and connections between said governor and said damper plate or valve whereby the volume of steam admitted to said chamber is automatically controlled to preserve the proportions of said vapor and said gases in the mixture in said chamber.

25. 4. In a gas producer, the combination of a retort, means in communication therewith whereby the gas generated therein is washed, scrubbed and dried, a pipe leading there-

from to the inlet port of an internal combustion engine, a distributing chamber in communication with the lower part of said retort, a vapor tank, means whereby gases are introduced to said chamber in volume proportionate to the quantity of gas drawn from said retort including a perforated drum in said vapor tank, a pipe leading therefrom and opening into said chamber, a damper plate or valve in said pipe, a blower casing communicating with said chamber and with the exhaust port of a gas engine, a wheel mounted in said casing having vanes whereby the exhaust gases from said engine will rotate said wheel, a centrifugal governor actuated by said wheel, and connections between said governor and said damper plate or valve whereby the volume of steam admitted to said chamber is automatically controlled to preserve the proportions of said vapor and said gases in the mixture in said chamber.

In witness whereof, I have hereunto affixed my signature, this 8th day of October, 1906, in the presence of two witnesses.

ERNEST DIGBY HOPCROFT.
